United States Patent Office

Des. 189,281
Patented Nov. 15, 1960

189,281

LIPSTICK CONTAINER

Thomas F. Slater, Waterbury, Conn., assignor to Scovill Manufacturing Company, Waterbury, Conn., a corporation of Connecticut

Filed May 20, 1960, Ser. No. 60,671

Term of patent 14 years

(Cl. D86—10)

Fig. 1

Fig. 2

Fig. 3

Fig. 1 is an elevational view of a lipstick container showing my new design;

Fig. 2 is a top plan view thereof; and,

Fig. 3 is a developed plan view of the surface ornamentation shown in Fig. 1.

The essential feature of my design resides in the portions shown in solid lines in the drawing.

I claim:

The ornamental design for a lipstick container, substantially as shown and described.
